O. C. RIXSON.
HOLDER FOR SWINGING CLOSURES.
APPLICATION FILED JAN. 26, 1917.

1,265,520.

Patented May 7, 1918.

UNITED STATES PATENT OFFICE.

OSCAR C. RIXSON, OF NEW ROCHELLE, NEW YORK.

HOLDER FOR SWINGING CLOSURES.

1,265,520.

Specification of Letters Patent. Patented May 7, 1918.

Application filed January 26, 1917. Serial No. 144,632.

To all whom it may concern:

Be it known that I, OSCAR C. RIXSON, a citizen of the United States, residing at New Rochelle, in the county of Westchester and State of New York, have invented certain new and useful Improvements in Holders for Swinging Closures, of which the following is a full, clear, and exact description.

This invention relates to holders for swinging closures, such as transoms, hinged windows, and the like. More particularly, the invention relates to holders consisting of a tubular member having a second member slidably mounted therein, which members are pivotally secured to the swinging closure and its frame. The free movement of the two members is retarded to a more or less extent to vary the resistance which the swinging closure offers to being moved from one position to another.

One of the objects of the invention is to provide a holder of this character in which the device for retarding the free movement of the members is concealed within the tubular member and is provided with an adjustment which, while concealed from view, is nevertheless accessible after the holder has been assembled.

With these and other objects in view, the invention contemplates a tubular member having a second member freely slidable therein, together with a device secured to one of these members, which is adapted to frictionally engage the other member and retard its free sliding movement. This device is concealed within the tubular member or casing and is preferably carried by the sliding rod. In the preferred form of the invention, an adjustable friction shoe is mounted upon the rod, which is provided with an adjusting screw which is accessible through an opening in the tubular member or casing.

In the accompanying drawings, the preferred embodiment of the invention is shown, and

Figure 1 shows a holder connected to a swinging closure and its frame, which holder is constructed in accordance with the principles of the invention.

Fig. 2 is a bottom plan view of the holder upon an enlarged scale.

Fig. 3 is a vertical longitudinal section through the holder.

Fig. 4 is an enlarged detail showing the friction device. 55

Figs. 5 and 6 are transverse sections upon the lines 5—5 and 6—6 of Fig. 4; and

Fig. 7 is a transverse section through the screw cap closing one end of the holder.

The holder may be used with any type of swinging closure, and in the drawings the frame of such a closure is partially shown and indicated 1, a swinging closure 2, which is also only partially shown, being hinged to the frame, as at 3. 60

The holder shown comprises a tubular member 4, consisting of a tube formed of brass or other suitable material permanently closed at one end, as at 5. The other end of the holder is closed by a screw cap 6 provided with a slot 7 therein, through which projects a flat rod 8 which is freely slidable within the casing or tubular member 4. The outer ends of this flat rod and the tubular member 4 are adapted to be pivotally secured to the swinging closure and its frame by any approved means. In the embodiment shown, a pin 9 passes through the outer end of the tubular member 4, and is pivotally secured to a bracket or support 10, which has a raised or offset middle portion which receives the head of the pin. The bracket is provided with openings 12, through which screws or other fastening devices 13 pass to secure the same rigidly to the frame 1 of the swinging closure. The outer end of the rod 8 is pivotally secured to an anchor piece 14, which anchor piece is provided with two upstanding ears or lugs 15, between which the end of the rod fits, the ears and rod being pivotally secured together by means of a pivot pin or rivet 16. The anchor piece 14 is rigidly secured to the rear face of the swinging closure by screws 17 or other suitable fastening means. 75 80 85 90 95

In so far as the construction has already been described, the rod 8 slides freely within the casing and the parts would therefore offer no resistance to retard the free movement of the swinging closure. To accomplish this a friction device is provided, which retards the relative sliding movement of the rod and the tubular member. In the embodiment shown, this friction device comprises two shoes 20 and 21, which shoes, as 100 105 will be clear from Fig. 4, are arc shaped and

of a curvature corresponding to the curvature of the inner wall of the tubular casing. The friction shoes are each provided with lugs 22 and 23, which lugs fit into slots 25 in the flat rod 8, and constrains these parts to move together. Interposed between one of these shoes and the flat rod is a strip 26, which is preferably of resilient metal. A set screw 27 threaded into the flat rod, bears 10 against this strip. An opening 28 formed in the shoe 21 is provided for the head of the set screw. By turning the screw 27, the strip 26 may be pushed outwardly to force the shoe 20 into frictional engagement with 15 the inner wall of the tubular member. The shoe 21 will also be forced into engagement with the other portion of the inner wall, since the edge of this shoe rests against the flat rod, as will be clear from Fig. 5. The 20 screw 27 therefore affords means for adjusting the frictional engagement between the shoes 20 and 21 and the tubular member, which may be regulated to any desired degree so that the desired resistance is provided to retard the free sliding movement 25 of the rod 8 and the tubular member, which will, in turn retard the free movement of the swinging closure.

If desired, the strip 26 may be of resilient 30 material and may be slightly bowed before the parts are assembled, so that when the screw 27 is adjusted to straighten it, as shown in the drawings, a tension will be exerted by the strip 26 in a direction to 35 maintain the shoe 20 in frictional engagement with the inner wall of the tubular member.

To adjust the set screw 27 when the holder 40 has been assembled, an opening 30 is provided in the tubular member, through which opening the end of a screw driver may be inserted to turn the set screw. By this construction, the friction device is entirely concealed from view, but nevertheless it is accessible 45 for adjustment so that when it is desired to vary the resistance required to move the swinging closure the same may be accomplished in an entirely simple manner.

The screw cap 6 is preferably provided 50 with a pin or screw 31, which is driven or screwed into a slot 32 in the threaded end of the tubular member 4 after the parts have

been assembled. This construction permits a relatively small angular movement of the screw cap, which may be required, due to the 55 irregularity of movement of the rod 8, but will prevent the inadvertent unscrewing of the cap 6.

I claim:

1. A holder for swinging closures, comprising a tubular member, a rod freely slideable in said tubular member, means for pivotally securing said tubular member and rod to a swinging closure and its frame, a pair of segmental shaped friction shoes carried by said rod and concealed within said tubular member, and means for adjusting said shoes to vary the friction between them and the inner wall of said tubular member. 60

2. A holder for swinging closures, comprising a tubular member, a flat rod freely slideable in said tubular member, means for pivotally securing said tubular member and rod to a swinging closure and its frame, arc shaped friction shoes having lugs fitting into 75 slots in said flat rod, and an adjusting screw carried by said flat rod engaging one of said friction shoes for varying the friction between said shoes and the inner wall of said tubular member. 70

3. A holder for swinging closures, comprising a tubular member, a rod freely slideable in said tubular member, means for pivotally securing said tubular member and rod to a swinging closure and its frame, a friction shoe carried by said rod concealed within said casing, an adjusting screw carried by said rod, and a piece interposed between said shoes and said adjusting screw. 80

4. A holder for swinging closures, comprising a tubular member, a telescoping rod in said member, means for pivotally securing said tubular member and rod to a swinging closure and its frame, a pair of friction shoes carried by said rod, an adjusting screw adapted to alter the frictional contact of said shoes and being arranged transversely of the tubular member and wholly within the same, said tubular member having an aperture in its side affording access 100 to said screw. 90

In witness whereof I subscribe my signature.

OSCAR C. RIXSON.
